UNITED STATES PATENT OFFICE.

HANS REICHEL, OF BRUNSWICK, GERMANY.

DESIGN FOR A HAND STAMP.

Application filed July 12, 1926, Serial No. 18,329, and in Germany June 16, 1926. Term of patent 14 years.

To all whom it may concern:

Be it known that I, HANS REICHEL, a citizen of the German Republic, and residing at Braunschweig, Germany, have invented a new, original, and ornamental Design for a Hand Stamp, of which the following is a specification, reference being had to the accompanying drawing, forming part thereof.

The figure is a perspective view of the hand stamp showing my new design.

I claim:

The ornamental design for a hand stamp as shown.

In testimony whereof I have signed my name to this specification.

HANS REICHEL.
